UNITED STATES PATENT OFFICE.

ANGUS F. HANNEY, OF CHICAGO, ILLINOIS, ASSIGNOR TO EUREKA ROUGH DRY PIN SYSTEM CO., OF CHICAGO, ILLINOIS.

LAUNDRY TAG.

1,411,092.

Specification of Letters Patent. Patented Mar. 28, 1922.

Application filed August 2, 1920. Serial No. 400,850.

To all whom it may concern:

Be it known that I, ANGUS F. HANNEY, a citizen of the United States, and a resident of the city of Chicago, county of Cook, and 5 State of Illinois, have invented certain new and useful Improvements in Laundry Tags, of which the following is a specification.

My invention relates to improvements in laundry tags, and has for its object the provision of an improved construction of this character constructed and arranged to be readily applied to articles to be laundered and readily and conveniently removed therefrom when desired.

15 Other objects will appear hereinafter.

The invention consists in the combinations and arrangements of parts hereinafter described and claimed.

The invention will be best understood by 20 reference to the accompanying drawings forming a part of this specification, and in which,

25 Fig. 1, is a perspective view of a laundry tag embodying the invention and illustrated in positions both before and after removal from the laundered article,

Fig. 2, a large transverse section of the tag shown in position of attachment to an article, and

30 Fig. 3, a similar view showing the tag in position of detachment from the article.

The preferred form of construction comprises a hollow flat sheet of metal body or casing 4 having a lip 5 projecting upwardly from the top thereof, said lip being adapted and arranged to receive an identifying number or mark stamped therein. A pin point 6 is secured in the casing 4 in position to project downwardly from one side 35 thereof. Co-operating with the pin point 6 is a locking lever 7 pivoted at 8 at the underside of the tag and carrying a cuff or ring 9 at its free end and adapted to fit over the pin point 6 as shown in Fig. 2 to hold said tag in engagement with an article to be laundered as indicated by the dotted lines in Fig. 1. The lever 7 is provided with a lug or projection 10 adapted to engage in notch 11 in a spring held detent 12 pivoted 40 at 13 in the casing 4. The casing 4 is provided with a transverse slot 14 and one end of the detent 12 traverses the lower end of said slot as shown.

45 A carrier bar 15 is provided and arranged to pass through the slots 14 of the laundry

tags; said bar being provided at its inner end with a stop lug 16 to facilitate releasable mounting of said bar on a suitable supporting bracket. The bar 15 is also provided at its outer end with a similar stop lug 17 which 60 prevents the accidental removal of the tags from the bar. The outer end of the bar 15 is somewhat narrower than the inner end, the two ends are connected by a cam surface 18 on the bottom of the bar. A removable 65 transverse stop 19 is arranged in the bar and rests loosely in a transverse opening therein immediately above the cam surface 18.

In use the carrier bar 15 is removably supported within a suitable bracket or support, 70 such a bracket or support being illustrated in my co-pending application filed as of even date herewith. The laundry tags which it is desired to remove from laundered articles are then placed in position on the outer end 75 of the bar 15 by passing the slots 14 therein over the outer end of said bar. When the desired number of tags have thus been placed in position on the bar, and this number will usually be the number of tags attached to 80 articles for a particular customer of the laundry, and the tags have been properly checked to show that all of the articles belonging to that customer are present, the pin 19 is removed from bar 15 and the tags 85 pushed in a body inwardly on to the larger inner end of the bar, thus causing the detents 12 of the different laundry tags to engage the cam surface 18, thus releasing the locking levers 7 of said tags and permitting the laundered articles to fall by gravity from the tags, a suitable basket or receptacle being set to catch said articles. The tags which are of course marked with the customer's identifying mark are thus 90 retained together and in order and may thus be readily removed from the carrier bar and retained for future use for that customer, or a new customer given the identifying mark which the tags bear. In this way the tags 95 may be readily and conveniently removed from the laundered articles and readily kept in association with each other, thus tending to prevent mistakes and greatly facilitating the conduct of the business of the laundry 100 in an orderly and efficient manner.

While I have illustrated and described the preferred form of construction for carrying my invention into effect, this is capable of variation and modification without depart- 110

ing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

- 10 1. A device of the class described comprising a body; a pin point projecting from said body; a swingable lock extending from said body and engaging said pin point; and a detent on said body holding and releasing said lock, substantially as described.
- 15 2. A device of the class described comprising a body; a pin point projecting downwardly from said body; a vertically swinging lock on said body engaging over said pin point; and a detent on said body holding and releasing said lock, substantially as described.
- 20 3. A device of the class described comprising a body; a pin point projecting from said body; a lock on said body co-operating with said pin point; and a detent on said body holding and releasing said lock, there being a slot in said body and said detent traversing said slot, substantially as described.
- 25 4. A device of the class described comprising a body; a pin point projecting downwardly from said body; a vertically swinging lock on said body co-operating with said pin point; and a detent on said body

holding and releasing said lock, there being a slot in said body and said detent traversing said slot, substantially as described.

5. A device of the class described comprising a hollow flat casing having a marking lip projecting from the top thereof; a pin point projecting from the bottom of said casing; a locking lever pivotally mounted on the bottom of said casing and having a cuff at its free end adapted to engage over 45 said pin point and swing downwardly therefrom; and a spring held detent in said casing automatically engaging said locking lever to lock the same with said cuff in operative relation with said pin point, there 50 being a slot in said casing and said detent traversing said slot, substantially as described.

6. A laundry tag of the class described comprising a body; a pin point projecting 55 downwardly from said body; a swingably mounted lock on said body engaging over said pin point; and a detent engaging said lock for holding and for releasing said lock, said body having an opening through which 60 said detent is adapted to be engaged and operated, substantially as described.

In testimony whereof I have signed my name to this specification in the presence of two subscribing witnesses.

ANGUS F. HANNEY.
